UNITED STATES PATENT OFFICE.

DANIEL HOGAN, OF NEW YORK, N. Y., ASSIGNOR TO THE MEINECKE & COMPANY, OF SAME PLACE.

DESIGN FOR A BED-PAN.

SPECIFICATION forming part of Design No. 32,788, dated June 5, 1900.

Application filed May 9, 1900. Serial No. 16,094. Term of patent 14 years.

To all whom it may concern:

Be it known that I, DANIEL HOGAN, a citizen of the United States, residing in the borough of Manhattan, New York city, in the county and State of New York, have invented and produced a new and original Design for a Bed-Pan, of which the following is a specification.

This design consists in a bed-pan having a concave front edge, a backwardly-sloping portion under said edge, elevated or thigh-supporting portions, and a depressed spout portion.

The design is illustrated in the annexed drawings, in which—

Figure 1 is a perspective view of the pan embodying the design. Fig. 2 is a sectional side elevation of the pan. Fig. 3 is a plan view of the pan. Fig. 4 is a section along *xx*, Fig. 3.

The concave front edge is shown at 1. Under this edge is the backwardly-sloping por-

tion 2. The swelling or elevated thigh-supporting portions are shown at 3, and the spout 4 is open at the top and is depressed or lies below the level of the parts 3. The top ledge 5, just back of the front edge 1, slopes slightly downward toward the back or spout of the pan, or, in other words, slopes toward or into the opening or mouth of the pan.

The design gives a striking and characteristic appearance.

What I claim as new, and desire to secure by Letters Patent, is—

The design for a bed-pan as herein shown and described.

In testimony whereof I have hereunto set my hand in the presence of two subscribing witnesses.

DANIEL HOGAN.
